UNITED STATES PATENT OFFICE

2,219,612

ELECTRIC REACTION FURNACE

Bernhard Berghaus, Berlin-Lankwitz, and Wilhelm Burkhardt, Berlin-Grunewald, Germany;
said Burkhardt assignor to said Berghaus

Application July 14, 1938, Serial No. 219,294
In Germany August 26, 1937

7 Claims. (CL. 13—31)

This invention relates to an annealing or melting furnace operating under reduced pressure, and pertains to an arrangement wherein the conducting crucible in which the annealing or melting material is accommodated is heated in a metallic vacuum chamber by a gas discharge with respect to which the crucible is permanently or temporarily connected as a cathode. The reduced pressure at which the heating of the crucible takes place is so chosen that the crucible is covered by the glow of the gas discharge preferably completely. The pressure may amount to 40 to 0.001 and preferably 5 to 0.01 millimeters of mercury.

15 When the crucible is heated by a direct current voltage applied to the path of discharge, the crucible is connected to the negative terminal of the source of voltage and the vacuum vessel may carry the positive voltage. Preferably, one or 20 more electrodes arranged within the housing are connected to the positive pole of the direct current voltage. This arrangement has the advantage that the vessel does not carry any dangerous voltages during the operation. The crucible is 25 mounted on one or more supports introduced in an insulated and vacuum-tight manner. One or all the supports may take over the conduction of the current to the negative pole of the source of voltage. Neutral supports may consist of insulating material such as porcelain, quartz or other sintered bodies. The supports and the conductors are hollow and their inner walls are cooled. Water, oil or compressed air may be used as the 30 cooling means. The cooling of the conductors is necessary in order to prevent the insulation and sealing material provided between the conductor and the vessel or the screen from being burnt. The cooling of the conductor or of the supports is effected along such a length that no substantial drop in temperature occurs at the points of contact with the crucible. A thermo-element for measuring the temperature is introduced through one of the supports in a vacuum-tight manner. In order to obtain an exact temperature measurement the thermo-element projects into the crucible. In order to protect the thermo-element it is preferably surrounded by the wall of the crucible. Use may be made also of only one support which serves at the same time as a conductor and as a support for the thermo-element. When the crucible is heated by an alternating current voltage applied to the path of discharge one or more electrodes are connected with one terminal of the source and the crucible with the 55 other terminal of the alternating current voltage.

The invention is illustrated diagrammatically and by way of example in the accompanying drawings, in which:

Figure 1 is a section through an annealing and melting furnace working at reduced pressure with a melting crucible for heating by glow current;

Figure 2 is a plan view of the three supports for the melting crucible according to Figure 1;

Figure 3 is a middle sole support of the melting crucible on an enlarged scale;

Figure 4 is a diagram of connections for direct current operation and

Figure 5 is a diagram of connections for alternating current operation.

In Fig. 1, which shows a section through an annealing and melting furnace 1 for operation at reduced pressure provided with a crucible 2 filled with melting material for heating with a glow current, the crucible 2 is supported on three metal supports 5, 6, 7 mounted in the vessel 4. The housing is closed in a vacuum-tight manner by a cover 3, and the supports serve at the same time to supply the negative voltage to the crucible. These supports and current leads are introduced in an insulated manner into the vacuum vessel 4 and are screened by metallic sleeves 8. Current is supplied to the supports by means of cables 9 and the parts 10, 11 and the clamping ring 12 consist of insulating material, the insulator 11 completely covers a flange 13 of the current lead which may be made hollow and be cooled by air so that no disturbing additional discharges take place. The supports of the crucible carry cap members 15 to prevent impurities from falling into the space between the current leads and the sleeves. The crucible 2 is provided with a recess 60 in which a thermo-element 17 is mounted which is introduced into the vacuum vessel 4 similarly insulated and screened by a sleeve 8a. The outer or connecting ends of the thermo-element are indicated at 18 and a metallic screening sleeve or tubular member 19 surrounds the thermo-element. The tubular member 19 and the screening sleeve 8a are insulated and sealed with respect to the housing 4 by insulating rings 20 and 21.

The vacuum vessel 4 is provided with a jacket 22 to which a cooling medium such as water or oil is supplied through the pipe connection 23, being discharged through the pipe connection 24. A pipe connection for a vacuum pump is shown at 25. Indifferent or reducing gases such as hydrocarbons may be supplied by the pipe connection 26. The cover 3 of the vacuum vessel is provided with a jacket 28 as well as with

5 pipe connections 29 and 30 for the supply and discharge of the cooling medium. An inspection hole is illustrated at 31 provided with a vacuum tight window. A packing ring 32 is provided between the housing 4 and the cover 3 and clamps 33 are arranged for securing the cover in position.

10 In Fig. 3 only one support 34 carries the crucible 2. The support is at the same time a current lead and support for the thermo-element 17. The support 34 is hollow and the cooling medium may be introduced through the pipe 35 and discharged through the pipe connection 36. The insulating ring 37 covers the flange 38 of the current lead completely. An insulating ring 39 is provided for clamping the flange 38 in position by means of bolts 41. The insulating ring or disk 37 is sealed with respect to the housing 4 by means of a soft metal ring 40. Likewise the 15 flange 38 is sealed with respect to the insulating disk 37 by means of a soft metal ring 41.

20 One of the metal screens in Fig. 3 is formed of two sleeves 44 and 44a. The upper sleeve 44 is removable so as to be exchanged without removing the lower sleeve 44a. The other screen is formed by a sleeve 45 which surrounds the sleeve 44a in a spaced relation to provide an annular space therebetween. The sleeve 44a carries a cap member 62 for preventing dirt from 25 falling into the annular space between the sleeve 45 and the sleeve 44a. Another cap member 43 is provided for preventing foreign particles from 30 entering the annular space between the conductor 34 and the sleeve 44. The upper end of the conductor 34 engages the crucible in a recess 60a.

35 A diagram of connections for heating the crucible 2 by direct current is shown in Fig. 4. A source of direct current is provided by a generator 46 and a negative terminal 63 thereof is connected to the crucible by the cables 9 in Fig. 1 or the wire 42 in Fig. 3. The positive terminal 40 of the generator may be connected to the housing 4 by means of a circuit which includes a resistor 47 and a switch 48. The positive terminal 45 may also be connected to auxiliary electrodes 50 and 51 arranged within the housing by means of a circuit which includes the resistor 47 and a switch 49.

45 A circuit arrangement for heating the crucible 50 by means of alternating current is illustrated in Fig. 5 wherein one terminal of a secondary winding 52 of a transformer is adapted to be connected to the crucible 2 through a switch 53. The other terminal of the secondary 52 is connected 55 to the auxiliary electrodes 50 and 51.

60 The screening has the advantage that large electrical energies can be introduced in a reliable manner into the vacuum vessel in the case of a glow discharge, without damaging the insulating 65 parts or sealings. The advantages of the glow current heating reside in the fact that the electrical energy is released directly at the material of the crucible, the crucible material thus acting as a heating element, whereby a favourable transmission of heat with good efficiency is obtained. The walls of the vacuum chamber which may be cooled or heat-insulated are maintained at such a temperature that they are capable of withstanding the atmospheric pressure.

70 What we claim is:

1. In a gas discharge heating or annealing furnace, a separable sealed metal housing providing a vacuum vessel, the lower portion of said housing having a plurality of openings therein, a rigid conductor extending upwardly through each of

5 said openings, a conducting crucible for receiving material to be heated arranged within said housing engaging ends of said conductors so as to be supported within the vessel in a spaced relation with respect to the housing, means insulating and sealing said conductors with respect to said housing, a screening sleeve surrounding each of said conductors in a spaced relation adjacent said housing to provide an annular space between each sleeve and the respective conductor, and a cap member associated with each conductor for preventing impurities from passing downwardly into the annular spaces.

10 2. In a gas discharge heating or annealing furnace, a separable sealed metal housing providing a vacuum vessel, the lower portion of said housing having a plurality of openings therein, a rigid conductor extending upwardly through each of said openings, a conducting crucible for receiving material to be heated arranged within said housing engaging ends of said conductors so as to be supported within the vessel in a spaced relation with respect to the housing, means insulating and sealing said conductors with respect to said housing, said crucible having a recess 15 therein, a tubular member extending through another opening in the housing into said recess, means insulating and sealing said tubular member with respect to said housing and a thermo element arranged in said tubular member terminating in said recess.

20 3. In an electric reaction furnace, a separable sealed metal housing providing an evacuable vessel, the lower portion of said housing having a plurality of openings therein, a rigid conductor 25 extending upwardly through each of said openings, a conducting crucible for receiving material to be heated arranged within said housing engaging the ends of said conductors so as to be supported within said vessel in a spaced relation 30 with respect to the housing, means arranged outside the vessel insulating and sealing said conductors with respect to the housing, and a screening sleeve surrounding each of said conductors in a spaced relation adjacent said housing to 35 provide an annular space between each sleeve and the respective conductor.

4. In an electric reaction furnace, a separable sealed metal housing providing an evacuable vessel, the lower portion of said housing having an 40 opening therein, a crucible for receiving material to be heated supported within said housing in a spaced relation with respect to the housing, said crucible having a recess 45 therein, a thermo-element extending through the opening in said housing and into said recess, a tubular member surrounding said thermo-element and extending through said opening into said recess, means insulating and sealing said tubular member with respect to said housing, and a screening sleeve 50 surrounding said tubular member in a spaced relation adjacent said housing to provide an annular space between the sleeve and said tubular member.

5. In an electric reaction furnace, a separable sealed metal housing providing an evacuable vessel, the lower portion of said housing having an 55 opening therein, a rigid conductor extending upwardly through said opening, a conducting crucible having a recess in the lower portion thereof, 60 said crucible being adapted to receive material to be heated and arranged within said housing engaging the end of said conductor within said recess so as to be supported on the rigid conductor in a spaced relation with respect to the hous- 65

ing, means arranged outside the vessel for insulating and sealing said conductor with respect to said housing, and a screening sleeve surrounding said conductor in a spaced relation adjacent said housing to provide an annular space between said sleeve and the conductor.

6. In an electric reaction furnace, a separable sealed metal housing providing an evacuable vessel, the lower portion of said housing having a plurality of openings therein, a rigid conductor extending upwardly through each of said openings, a conducting crucible for receiving material to be heated arranged within said housing engaging the ends of said conductors so as to be supported within said vessel in a spaced relation with respect to the housing, means arranged outside the vessel insulating and sealing said conductors with respect to the housing, a screening sleeve surrounding each of said conductors in a spaced relation adjacent said housing to provide an annular space between each sleeve and the respective conductor, each conductor being solid adjacent said crucible and hollow adjacent said housing for receiving a cooling medium to cool the conductors adjacent the insulating and sealing means without substantially affecting the temperature of the conductors adjacent the crucible.

7. In an electric reaction furnace, a separable sealed metal housing providing an evacuable vessel, the lower portion of said housing having an opening therein, a rigid conductor extending upwardly through said opening, a conducting crucible having a recess in the lower portion thereof, said crucible being adapted to receive material to be heated and arranged within said housing engaging the end of said conductor within said recess so as to be supported in a spaced relation with respect to the housing, means insulating and sealing said conductor with respect to said housing, a screening sleeve surrounding said conductor in a spaced relation adjacent said housing to provide an annular space between said sleeve and the conductor, a thermo-element extending through said conductor terminating in said recess, said conductor being hollow adjacent said housing, and means for introducing a cooling medium into the hollow portion of said conductor for cooling the same adjacent the insulating and sealing means without any substantial cooling of the conductor adjacent the crucible.
